PROCESS FOR SOLVENT EXTRACTION OF
MINERAL OIL

David R. Merrill, Long Beach, and Philip Subkow,
Los Angeles, Calif., assignors to Union Oil Com-
pany of California, Los Angeles, Calif., a cor-
poration of California

Application November 12, 1932, Serial No. 642,371

13 Claims. (Cl. 196—13)

This invention relates to a process for the solvent extraction of mineral oil. More specifically it relates to a process for the production of lubricating oil from petroleum by the use of solvents.

In our copending application Serial No. 639,341, filed October 24, 1932, and which has since issued as Patent No. 2,103,591, we have disclosed and claimed a multistage countercurrent solvent extraction process in which the extract phase from a preceding stage is chilled to produce a reject, and wherein this reject is countercurrently extracted in the next succeeding zone with a selective solvent and the extract phase coming from a later solvent extraction stage.

One of the distinctive characteristics of a lubricating oil is its viscosity. Its usefulness as a lubricant depends, at least in part, upon its viscosity. For many purposes lubricants are desired whose viscosity will vary as little as possible with variations in temperature, i. e., which have low temperature viscosity susceptibilities. Those fractions which exhibit a low temperature viscosity susceptibility may be referred to as paraffinoid oils whereas the fractions which exhibit a high temperature viscosity susceptibility are referred to as non-paraffinoid oils.

The heavy oil fractions of many crude oils, from which lubricating oils are produced, consist of a mixture of hydrocarbons some of which exhibit a low temperature viscosity susceptibility and some of which exhibit a high temperature viscosity susceptibility. In order to produce superior lubricating oil from such hydrocarbon mixtures, those oils present having a high viscosity temperature susceptibility are separated from the oils present which exhibit a low temperature viscosity susceptibility. Solvent extraction is one of the methods employed to separate the undesirable oil from the desirable oil. Solvents, such as aniline, furfural, nitrobenzene, selenium oxychloride, sulphur dioxide or dichlorethyl ether are capable, under the proper conditions of temperature and pressure, of dissolving the fractions present which are non-paraffinoid in character. These solvents form relatively heavy solutions with the non-paraffinoid oil fractions and can be separated from the insoluble paraffinoid oil fractions by settling. That portion insoluble in the extracting solvent is termed the raffinate while the soluble portion is known as the extract.

In the following disclosure of our process, wherever dichlorethyl ether is mentioned it will be understood that the other solvents recited above may likewise be employed. B B' dichlorethyl ether, $\text{ClCH}_2\text{CH}_2\text{OCH}_2\text{CH}_2\text{Cl}$, has a preferential

solvent action on aromatic or non-paraffinoid components of the oil. However, we have found that when extraction is accomplished using this solvent, not all of the paraffinoid components are removed in the insoluble raffinate, nor are all of the non-paraffinoid components dissolved in the extract. In other words, the solvent is selective as to a large proportion of paraffinoid and non-paraffinoid components but its selectivity is not entirely complete. We have found that after the primary separation by extraction with dichlorethyl ether, the extract and raffinate may be further classified separately whereby the raffinate will in turn be divided into a second raffinate and a second extract and whereby the primary extract may be divided into another extract and another raffinate.

We have found that in the operation of our process we are able to obtain a raffinate of very high quality, i. e., having a large proportion of paraffinoid components and to obtain additional raffinates having successively smaller proportions of paraffinoid components as well as to obtain an extract high in the proportion of non-paraffinoid fractions. We have also found that temperature conditions during these extractions exert a great influence upon the character of the materials comprising the raffinate and extract. For instance, when the primary extraction is carried out at a relatively high temperature we have found, upon reduction of temperature of the solution of dichlorethyl ether and extract obtained from said primary extraction, that this extract may in turn become separable into two phases, a raffinate and an extract. This latter extract may again be treated similarly after another reduction in temperature and this process can be continued to produce as many intermediate fractions as desired.

Also, we have found, upon reduction of the temperature of the raffinate and upon the addition of an extracting solvent, such as acetone thereto, that this raffinate may in turn become separable into two phases, a raffinate and an extract to produce fractions having various proportions of paraffinoid components.

When the primary extraction with dichlorethyl ether is accomplished at relatively high temperatures, i. e., about 100° F. or more, the raffinate produced has a desirable large proportion of non-paraffinoid hydrocarbons, but the yield of this raffinate is small. Commercial operation necessitates further extractions at lower temperatures, i. e. 40° F. or 0° F., to obtain larger yields. In the extraction of certain oils with dichlorethyl

ether, alone, it is sometimes found that the raffinate is a viscid mass at the temperature necessary for extraction. This is particularly true when a wax-containing oil is subjected to such treatment. We have found that the presence of a light hydrocarbon, such as a petroleum fraction obtained by the rectification of natural gasoline, reduces the viscosity of this mixture whereby more efficient stratification and separation are accomplished.

As an example of such commercially available fractions, one composed of 6.72% ethane, 72.2% propane, 19.91% isobutane and 1.17% normal butane may be cited as satisfactory. It will be understood, however, that these merely illustrate the type of fractions which may be used and that the composition may vary. This fraction will hereafter be referred to as "propane" for purposes of simplicity. Also, in the operation of our process in which the raffinate from the primary extraction is further cooled in the presence of acetone for additional extraction, the viscosity of this raffinate may likewise be reduced by the addition of liquid propane.

We have also found that the presence of acetone in the further dichlorethyl ether extraction at lower temperatures of the extract produced in the primary extraction at high temperatures is advantageous, not only for its own solvent effect, which is similar to that of the dichlorethyl ether, but also because of its diluent action and its property of inhibiting the presence of wax in the extract phase.

The pressure to be employed in the operation of our process depends upon a number of factors, notably the temperature used and the amount of solvents employed. However, the pressure should be sufficient to accomplish the extraction while these solvents are liquid.

Therefore, it is an object of our invention to obtain by solvent extraction a number of fractions having varied proportions of paraffinoid components from mineral oil such as lubricating oil for example, which comprises paraffinoid and non-paraffinoid components.

Frequently such oil contains wax. It is a further object to dewax the oil in addition to treating it by successive extractions.

Another object is to correct for the lack of complete selectivity of the solvent by further selective extractions either of the raffinate or extract produced by the primary extraction, or by further selective extractions of both this raffinate and extract.

In the drawings,

Fig. 1 is a flow sheet of the principal steps involved in the operation of our process.

Figs. 2 and 2A are one form of apparatus which we may employ to carry out our process. The diagrammatic embodiments in Figs. 2 and 2A has been divided along line 2-2.

Referring to Fig. 1 the flow of the material indicated by the legends is in the direction of the arrows. The raffinate is that portion insoluble in the extracting solvent. The extract is that fraction soluble in the extracting medium. Figs. 2 and 2A show in greater detail the process outlined in Fig. 1.

Referring more particularly to Figs. 2 and 2A, oil containing wax to be subjected to treatment is stored in tank 5. It is removed therefrom by action of pump 6 in line 7 controlled by valve 8 and passes through coils 9 disposed in heater 10. From heater 10 this oil passes via line 11 into line 17. Dichlorethyl ether stored in tank 12 is 75

forced by pump 13 through line 14 controlled by valve 15 and through coil 16 also disposed in heater 10. Heat may be supplied to heater 10 by any usual means, not shown. The dichlorethyl ether then flows through line 17 commingling with the oil containing wax.

In order to facilitate proper intermixture of the waxy oil and dichlorethyl ether, a suitable agitator may be provided; for instance, orifice 19 mixer 18 constructed in the usual manner to cause successive passage of the liquids through constricted apertures in diaphragms consecutively interposed between relatively large chambers whereby intimate contact of the liquids is insured. From the mixer 18 the liquids pass via line 19 into primary separator 20 wherein the oil separates into two phases, a raffinate substantially insoluble in dichlorethyl ether and an extract soluble therein. However, at the temperature employed, a minor amount of the ether may also be dissolved in the raffinate.

This raffinate in separator 20 is removed therefrom by pump 23 in line 21 controlled by valve 22. Acetone is introduced into line 21 by passage from acetone storage 25 through line 26, valve 27, pump 28, lines 29 and 30, and valve 31. The mixture is then passed through orifice mixer 35, line 36 and line 37 for cooling by heat exchange in heat exchanger 38 with the material to be described below flowing through line 69. The raffinate and acetone mixture then flows through line 39 into which is introduced a stream of liquid propane. Propane, under pressure sufficient to be maintained in the liquid state, is stored in tank 40 and may be passed by action of pump 41 into line 39 via lines 42 and 44 controlled by valves 43 and 45, respectively. The cooled raffinate-acetone-propane mixture containing a small amount of dichlorethyl ether then passes through orifice mixer 46 and line 47 into separator 50 in which this mixture again separates into two phases; a raffinate solution in propane substantially insoluble in the solution of extract in acetone and dichlorethyl ether.

45 The raffinate solution in propane in separator 50 may contain some wax which must be removed. Consequently, this raffinate passes via line 51 controlled by valve 52 into expansion chamber 53 in which the pressure is reduced 50 sufficiently to cause evaporation of at least part of the propane with consequent internal refrigeration of the raffinate containing wax. The wax will precipitate from the oil at the low temperature produced. Propane vaporized in chamber 53 passes therefrom via line 55 controlled by valve 56 by action of pump 57 and thence into condenser coil 58 in which it is returned to liquid condition. Liquid propane is recycled to storage 40 by passage through line 59.

The mixture of raffinate, precipitated wax and remaining propane in chamber 53 may also contain a relatively small proportion of dichlorethyl ether and acetone not removed in separators 20 and 50. This mixture in 53 passes therefrom by action of pump 62 in line 63 controlled by valve 64 into filter press 65 wherein the wax is retained on the filter plates, while the wax-free filtrate is removed via line 66 controlled by valve 67. The wax remaining in filter 65 may be removed by any usual method.

70 The cold wax-free filtrate from 65 is next forced by pump 68 through a series of heat interchangers in order to raise its temperature before distillation of the remaining solvents from the oil. Accordingly, it passes via line 66 into

line 69 disposed in heat exchanger 38 to absorb heat from the material passing through line 37; thence via line 70 into line 71 situated in heat exchanger 72 to absorb heat from the material to be described below flowing through line 122, 5 thence via line 73 into line 74 disposed in heat exchanger 75 to absorb heat from the material to be described below flowing through line 140. The preheated wax-free filtrate from filter press 65 is then introduced into still 80 via line 76. 10

Distillation is effected in 80 by introduction of additional heat; for instance, by flow of steam through closed coil 81. The solvents are thereby removed from the raffinate which remains undistilled. This wax-free raffinate, therefore, is 15 that portion of the oil which is substantially insoluble in dichlorethyl ether and acetone. From column still 80 the wax-free raffinate is removed via line 82 and valve 83 by pump 84 into storage 85. Propane, together with any acetone and/or dichlorethyl ether present, vaporizes in still 80 and exits therefrom via line 86 controlled by valve 87. These vapors pass into condenser coil 88 and thence into separator 90 via line 89. Condensation of the acetone and ether is effected in 20 88 while the propane remains in vapor form. Propane vapors are removed from 90 by pump 91 via line 92 controlled by valve 93 to line 55 for return into liquid propane storage 40 in the manner above described.

Acetone and dichlorethyl ether are removed from separator 90 by pump 94 in line 95 controlled by valve 96. Line 95 connects with still 100 provided with closed steam coil 101. Acetone vaporized in still 100 escapes via line 102 controlled by valve 103 into condenser coil 104 and the acetone is returned to storage 25 by action of pump 105 in line 106. Dichlorethyl ether, undistilled in still 100, passes to storage 12 via line 107 and valve 108 by action of pump 109.

Returning now to separator 50, the extract solution in acetone and dichlorethyl ether is removed by pump 116 through valve 117 in line 115. Acetone may be introduced at this point by flow from storage 25 through line 26, valve 27, pump 28, valve 118 and line 119. The mixture of extract, ether and acetone is then intermixed in orifice mixer 120 after which it passes via line 121 into line 122 situated in heat exchanger 72 for cooling by heat exchange with the material described above flowing through line 71. From the heat exchanger 72 the mixture flows through line 123 into line 125 disposed in heat exchanger 124 to be cooled by heat exchange with the material described below flowing through line 152. The cooled mixture then passes through line 126 into separator 130 in which the mixture separates into two phases; a raffinate substantially insoluble in dichlorethyl ether and acetone and an extract soluble therein. The raffinate may, however, contain a minor proportion of the ether and acetone.

Following the course of the raffinate from separator 130, it is removed by action of pump 131 into line 132 controlled by valve 133. Acetone may be introduced into this line from storage 25 via line 26, valve 27, pump 28, line 134 and valve 135. Liquid propane may be sent into line 132 from storage 40 via line 42, pump 41, valve 43, line 136 and valve 137. The mixture flowing 70 75

through 132 is then intermingled by passage through orifice mixer 138 from which it passes by line 139 into line 140 situated in heat exchanger 75 in which it is cooled by heat exchange with the material above described flowing through line 74. From heat exchanger 75 the mixture passes into line 141 into which is also introduced cold liquid propane from line 153.

The manner in which this cold liquid propane is obtained is as follows: propane from storage 40 passes via pump 41, line 42, valve 43 into line 142 through expansion valve 143 and into propane cooler 145 in which the pressure is sufficiently reduced to partially vaporize the propane. This partial vaporization results in a drop in temperature in the liquid propane remaining in cooler 145. Propane vapors are removed by pump 146 via valve 147 in line 148 which connects with line 55 through which they pass for condensation and storage in 40 in the manner described above. Cold liquid propane is removed from cooler 145 by pump 149 through line 150 controlled by valve 151. This cold propane then passes through line 152 disposed in heat exchanger 124. The material, previously described, flowing through line 125 is thus cooled by heat exchange with the cold liquid propane in line 152. The propane then flows through line 153 which connects with line 141, described above.

The cold mixture of propane and raffinate from separator 130 then is intermingled in orifice mixer 154 and flows to separator 155 via line 156. Separation occurs therein into two phases; a raffinate solution in propane substantially insoluble in the dichlorethyl ether and acetone and an extract soluble therein. The raffinate, however, may contain a small proportion of ether and acetone as well as some wax which was not removed in primary separator 20. This raffinate is removed from separator 155 via line 157 controlled by valve 158 and is passed into expansion chamber 160. The pressure is reduced sufficiently therein to cause evaporation of at least part of the propane with consequent internal refrigeration of the raffinate containing wax. The wax will precipitate from the oil at the low temperatures attained.

50 Propane vaporized in chamber 160 passes therefrom via line 161 controlled by valve 162 by action of pump 163 and thence into lines 92 and 55 for condensation and return to liquid propane storage 40 as above described. The mixture of raffinate and precipitated wax and remaining propane in chamber 160 passes therefrom by action of pump 164 in line 165 controlled by valve 166 into filter press 167 wherein the wax is retained on the filter plates while the 55 wax-free filtrate is removed via line 168 controlled by valve 169. The wax remaining in filter 167 may be removed by any usual method. The cold wax-free filtrate from 167 is next forced by pump 170 into line 171 disposed in heat exchanger 172 to raise its temperature by heat exchange with the material to be described passing through line 205. The filtrate then passes through line 173 into column still 175 heated by closed steam coil 176. The raffinate is freed 60 therein of acetone, ether and remaining propane by distillation. This raffinate is removed by pump 177 in line 178 controlled by valve 179 and passes into storage 180.

The acetone, dichlorethyl ether and propane vapors in still 175 issue into line 183 controlled

by valve 184 and thence pass into condenser coil 185. They are cooled sufficiently to condense the acetone and ether. These materials pass by line 186 into separator 187 from which the propane vapors issue via line 188, valve 189 and pump 190 into lines 161, 92 and 55, as previously described, for liquefaction and recovery of the propane. The condensate in separator 187 comprising acetone and dichlorethyl ether passes through line 191, valve 192 and pump 193 for passage into line 95 and still 100, as previously described, for the separate recovery of these solvents.

Returning now to separator 155, the extract solution in acetone and dichlorethyl ether is removed by pump 195 through valve 196 via line 197 which connects with line 249 through which flows a mixture described below.

Again referring to the separator 130, the extract soluble in acetone and dichlorethyl ether is removed by pump 198 through valve 199 in line 200. Acetone from tank 25 is introduced into this line by passage through line 26, valve 27, pump 28, line 201 and valve 202. Extract, previously described, from separator 50 is likewise introduced into this line via line 110, pump 111 and valve 112.

The mixture in line 200 is then intermingled in orifice mixer 203 and is passed via line 204 into line 205 disposed in heat exchanger 172 to be cooled by heat exchange with the medium described above flowing through line 171. The cooled extract in line 205 then passes via line 206 into separator 210 in which a separation of phases is accomplished. The raffinate, i. e., insoluble portion containing wax not previously removed in separators 20 and 130, exits from separator 210 by action of pump 211 in line 212 controlled by valve 213. Cold liquid propane, chilled in cooler 145 as previously described, is introduced into line 212 from propane cooler 145 via pump 149, line 150, valve 151, line 214 and valve 215.

This mixture of raffinate, wax and liquid propane is then expanded through valve 216 into separator 217. The pressure is reduced sufficiently therein to cause evaporation of at least part of the propane with consequent internal refrigeration whereby the wax will precipitate at the low temperatures attained. Propane vaporized in chamber 217 passes therefrom via line 218 controlled by valve 219 by action of pump 220 and thence into lines 148 and 55 for condensation and return to liquid propane storage 40 as above described.

The mixture of raffinate, remaining propane and precipitated wax in chamber 217 passes therefrom by action of pump 221 in line 222 controlled by valve 223 into filter press 225 wherein the wax is retained on the filter plates while the wax-free filtrate is removed via line 226 controlled by valve 227 by action of pump 228 into column still 230 heated by closed steam coil 231. The raffinate is freed therein of acetone, dichlorethyl ether and remaining propane by distillation. This raffinate is removed by pump 232 in line 233 controlled by valve 234 into storage 235.

The acetone, dichlorethyl ether and propane vapors in still 230 issue into line 236 controlled by valve 237 and thence pass into condenser coil 238. They are cooled sufficiently to condense the acetone and ether. These materials pass via line 239 into separator 240 from which the propane vapors issue via line 241, valve 242, and

75 pump 243 into lines 218, 148 and 55 for liquefaction and recovery of the propane as previously described. The condensate in separator 240 comprising acetone and dichlorethyl ether passes

5 through line 244, valve 245 and pump 246 into line 55 and still 100 for the separate recovery of these solvents as previously described.

Again referring to separator 210, the extract solution in acetone and dichlorethyl ether is removed by pump 247 through valve 248 via line 249 into which issues the previously described extract from separator 155 via line 197. The mixed extracts then pass via line 249 into column still 250 heated by closed steam coil 251. The extract is freed therein by distillation of acetone, dichlorethyl ether and any propane which may be present. This extract is removed by pump 252 in line 253 controlled by valve 254 into extract storage 255.

20 The acetone, dichlorethyl ether and propane vapors in still 250 issue into line 256 controlled by valve 257 and thence pass into condenser coil 258. They are cooled sufficiently to condense the acetone and ether. These materials pass via line 259 into separator 260 from which the propane vapors issue via line 261, valve 262, pump 263 into lines 218, 148 and 55 for liquefaction and recovery of the propane, as previously described.

25 The condensate in separator 260 comprising acetone and dichlorethyl ether passes through line 264, valve 265 and pump 266 into line 95 and still 100 for the separate recovery of these solvents, as described above.

30 It will be observed that in the operation of our process according to the exemplary method recited above and according to the flow sheet, Fig. 1, oil containing wax may be successively fractionated by solvent extraction whereby several fractions having varied characteristics may be obtained. For instance, if the oil to be treated is a waxy lubricating oil containing paraffinoid and non-paraffinoid components, the extraction with dichlorethyl ether in separator 20 fractionates the oil into a raffinate having a relatively large proportion of paraffinoid hydrocarbons and into an extract having a large proportion of non-paraffinoid fractions.

35 The paraffinoid content of this raffinate is further increased by the extraction at a lower temperature in separator 50 in the presence of acetone, propane and any dichlorethyl ether which may pass with the raffinate from separator 20. The raffinate from 50, after wax removal in filter 65 and after solvent removal in still 80, has 40 the largest proportion of paraffinoid components of any of the fractions obtained by our process. It is stored in tank 85.

45 The extract obtained by separation with dichlorethyl ether in separator 20 is then subjected to a series of extractions for further separation of paraffinoid from non-paraffinoid components in the presence of dichlorethyl ether, acetone and propane at successively lower temperatures in separators 130 and 210. For instance, the temperatures which may prevail in separators 20, 55 130 and 210 may be 140° F., 40° F. and 0° F., respectively.

50 These separations may not be sufficient to obtain the desired number of fractions. Therefore, the raffinate from separator 130 may, like the raffinate from separator 20, be further classified. Reduction of temperature for this phase separation may be accomplished by the introduction via line 153 of cold liquid propane chilled in the manner above described into the raffinate

from separator 130. This material in separator 155 then separates into a raffinate and an extract. This raffinate from 155, after wax removal in filter 167 and solvent removal in still 175, has the second largest proportion of paraffinoid components of the fractions obtained by our process. It is stored in tank 180.

The extract portions from separators 50 and 130 may be treated conjointly as described above, or separately. The raffinate from the extraction in separator 210, after wax removal in filter 225 and after solvent removal in still 230 contains the third largest proportion of paraffinoid components. It is stored in tank 235.

The extract phases from separators 155 and 210 may be treated together, as described, or separately. This extract, after removal of the solvents in still 250, contains the least proportion of paraffinoid components and the largest proportion of non-paraffinoid fractions. It is stored in storage 255.

It is to be understood that while the foregoing example relates to successive solvent extraction of lubricating oil containing wax, our invention is not limited thereto because it is applicable to the treatment of mineral oils and hydrocarbons both heavier and lighter than lubricating oils. Furthermore, our invention is not limited to the same number of phase separations described but may be varied by omission of the extraction occurring in separator 210 or the number of separations may be increased if the need should arise. Many other variations may be made without departing from the spirit of our invention.

We claim:

1. A process of separating paraffinoid and non-paraffinoid components from mineral oil which comprises mixing said oil with dichlorethyl ether, separating the extract soluble therein from the raffinate insoluble in dichlorethyl ether, mixing said raffinate with liquid propane, reducing the temperature of said raffinate to separate said raffinate into a second extract and raffinate and separating said second extract from said raffinate.

2. A process of separating paraffinoid and non-paraffinoid components from mineral oil which comprises mixing said oil with dichlorethyl ether, separating the extract soluble therein from the raffinate insoluble in dichlorethyl ether, mixing said raffinate with acetone, and separating the extract soluble in said acetone from the raffinate insoluble therein.

3. A process of separating paraffinoid and non-paraffinoid components from mineral oil which comprises mixing said oil with dichlorethyl ether, separating the extract soluble therein from the raffinate insoluble in dichlorethyl ether, mixing said raffinate with acetone, reducing the temperature of said raffinate, and separating the extract soluble in said acetone from the raffinate insoluble therein.

4. A process of separating paraffinoid and non-paraffinoid components from mineral oil comprising mixing said oil with dichlorethyl ether, separating the extract soluble therein from the raffinate insoluble in dichlorethyl ether, mixing said raffinate with liquid propane and acetone, and separating the extract soluble in said acetone from the raffinate insoluble therein.

5. A process of separating paraffinoid and non-paraffinoid components from mineral oil comprising mixing said oil with dichlorethyl ether, separating the extract soluble therein from the raffinate insoluble in dichlorethyl ether, mixing

said raffinate with liquid propane and acetone, cooling said raffinate and separating the extract soluble in said acetone from the raffinate insoluble therein.

6. A process of separating paraffinoid and non-paraffinoid components from mineral oil comprising mixing said oil with dichlorethyl ether, separating the extract soluble therein from the raffinate insoluble in dichlorethyl ether, mixing liquid propane with said extract and dichlorethyl ether, and separating an insoluble raffinate and a soluble extract from said mixture of propane, dichlorethyl ether and extract from the first extraction.

7. A process of separating paraffinoid and non-paraffinoid components from mineral oil comprising mixing said oil with dichlorethyl ether, separating the extract soluble therein from the raffinate insoluble in dichlorethyl ether, mixing liquid propane with said extract and dichlorethyl ether, reducing the temperature of said extract, and separating an insoluble raffinate and a soluble extract from said mixture of propane, dichlorethyl ether and extract from the first extraction.

8. A process of separating paraffinoid and non-paraffinoid components from mineral oil which comprises extracting said oil in a first extraction stage with dichlorethyl ether, separating the raffinate insoluble in said ether from the extract soluble therein, reducing the temperature of said extract, mixing liquid propane with said extract and dichlorethyl ether, separating the raffinate insoluble in said second extraction stage from the extract remaining dissolved in said dichlorethyl ether, mixing acetone with the extract from said second extraction stage dissolved in dichlorethyl ether, cooling said extract and separating the raffinate insoluble in said solvents from the extract soluble therein.

9. A process of separating paraffinoid and non-paraffinoid components from mineral oil which comprises extracting said oil in a first extraction stage with dichlorethyl ether, separating the raffinate insoluble in said ether from the extract soluble therein, mixing acetone with said raffinate, reducing the temperature of said raffinate, separating raffinate insoluble in said second raffinate extraction from extract soluble in said acetone, mixing liquid propane with said extract and dichlorethyl ether from the first extraction stage, reducing the temperature of said extract, separating raffinate insoluble in said second extract extraction from extract soluble in said dichlorethyl ether.

10. A process of separating paraffinoid and non-paraffinoid components from mineral oil which comprises mixing said oil with dichlorethyl ether, separating the extract soluble therein from the raffinate insoluble in dichlorethyl ether, reducing the temperature of said extract to separate said extract into a second raffinate and extract, separating said second raffinate from said extract, cooling said second raffinate, adding acetone to said second raffinate, and separating the raffinate insoluble in said acetone from the extract soluble therein.

11. A process of separating paraffinoid and non-paraffinoid components from mineral oil which comprises mixing said oil with dichlorethyl ether, separating the extract soluble therein from the raffinate insoluble in dichlorethyl ether, mixing liquid propane with said extract and dichlorethyl ether, reducing the temperature of said extract, separating a second raffinate dissolved in said liquid propane from the extract dissolved in

dichlorethyl ether, mixing acetone with said second raffinate dissolved in liquid propane, cooling said second raffinate, separating extract dissolved in said acetone from raffinate undissolved therein.

12. A process of separating paraffinoid and non-paraffinoid components from mineral oil which comprises extracting said oil in a first extraction stage with dichlorethyl ether, separating the raffinate insoluble in said ether from the extract soluble therein, mixing acetone with said raffinate, reducing the temperature of said raffinate, separating raffinate insoluble in said second raffinate extraction from extract soluble in said acetone, mixing liquid propane with said extract and dichlorethyl ether from the first extraction stage, reducing the temperature of said extract, separating raffinate insoluble in said second extract extraction from extract soluble in said di-

chlorethyl ether, mixing said extract and dichlorethyl ether from said second extract extraction with said extracts and acetone from said second raffinate extraction, cooling said mixture and separating an extract and raffinate therefrom.

13. A process of extracting mineral oils comprising non-paraffinoid components and paraffinoid components including wax which comprises mixing said oil with dichlorethyl ether, separating the extract soluble therein from the raffinate including wax insoluble in dichlorethyl ether, mixing said raffinate with liquid propane and acetone, cooling said raffinate, separating the extract soluble in said acetone from the raffinate including wax insoluble therein, cooling said raffinate to precipitate the wax and separating the wax from the raffinate.
